US0D1055309S

(12) **United States Design Patent** (10) **Patent No.:** **US D1,055,309 S**
(45) **Date of Patent:** **** Dec. 24, 2024**

(54) **CONTAINER FOR PROVIDING REAGENTS**

(71) **Applicant:** **LIFE TECHNOLOGIES CORPORATION**, Carlsbad, CA (US)

(72) **Inventors:** **Axel Unger**, Munich (DE); **Elgin Meike Toepfer Taylor**, San Francisco, CA (US); **Nicole Busch**, Oldendorf (DE); **Tom Hynek**, Greiveldange (LU); **Fredrik Aidehag**, Stockholm (SE); **Todd Pelman**, San Francisco, CA (US); **Martin Naley**, Winchester, MA (US)

(73) **Assignee:** **LIFE TECHNOLOGIES CORPORATION**, Carlsbad, CA (US)

(**) **Term:** **15 Years**

(21) **Appl. No.:** **29/757,423**

(22) **Filed:** **Nov. 5, 2020**

Related U.S. Application Data

(60) Continuation of application No. 29/661,397, filed on Aug. 27, 2018, now Pat. No. Des. 901,717, which is a division of application No. 29/552,677, filed on Jan. 25, 2016, now Pat. No. Des. 829,923, which is a continuation of application No. 15/001,047, filed on Jan. 19, 2016, now abandoned, which is a continuation of application No. 13/664,266, filed on Oct. 30, 2012, now Pat. No. 9,272,896, said application No. 29/552,677 is a continuation of application No. 12/135,988, filed on Jun. 9, 2008, now Pat. No. 8,652,424, said application No. 13/664,266 is a continuation of application No. 11/497,093, filed on Aug. 1, 2006, now Pat. No. 8,329,470, said application No. 12/135,988 is a (Continued)
